DESIGN FOR A FUR-LINED SHOULDER PAD FOR THERAPEUTIC PURPOSES

William Hamburger, New York, N. Y., assignor of
one-half to Adolf Hamburger, New York, N. Y.

Application December 23, 1944, Serial No. 117,075

Term of patent 3½ years

(Cl. D83—1)

To all whom it may concern:

Be it known that I, William Hamburger, a citizen of no country (having applied for U. S. citizenship), and residing in the city, county, and State of New York, have invented a new, original, and ornamental Design for a Fur-Lined Shoulder Pad for Therapeutic Purposes, of which the following is a specification, reference being made to the accompanying drawing, forming a part thereof.

Fig. 1 is an inside plan view of a fur-lined shoulder pad for therapeutic purposes showing my new design.

Fig. 2 is a perspective view of the pad shown in Fig. 1 in applied position.

I claim:

The ornamental design for a fur-lined shoulder pad for therapeutic purposes, substantially as shown.

WILLIAM HAMBURGER.
